ASEPTIC PACK

Howard A. Pringle, Canton, Mass.

Application October 11, 1934, Serial No. 747,953

13 Claims. (Cl. 206—43)

This invention relates to improvements in aseptic packs comprising hypodermic syringe outfits for certain treatments notably for such as usually must of necessity be self administered.

5 The utility of such packs may be most readily appreciated by consideration of the circumstances attendant such self treatments and the essential sterile condition of the instruments which must be maintained. Those suffering from such diseases as diabetes are dependent upon insulin injections at regular intervals, and while the patient eventually acquires a certain degree of skill and care, there is always present the possibility that some precaution against infection has been overlooked.

10 My invention provides a complete outfit including, beside the hypodermic syringe, a swab and a supply of alcohol, and spare needles confined in liquid tight compartments in which the sterile 15 condition of the instruments is ensured. For this outfit I provide a pack which may be conveniently carried as in a pocket without the danger of leakage or breakage, and which while invaluable to patients and doctors alike because of its aseptic 20 condition, is also of great use because the pack may be set upright and the instruments contained therein be supported as by a rack or stand, thus not only facilitating treatments, but also further ensuring the sterility of the instruments.

25 30 While I have suggested the use of my invention as practised by those who rely on self treatment and who, therefore, may be assumed to have a degree of skill commensurate with their experience, it will be readily appreciated that my pack will be even more invaluable to those unskilled persons who will require such treatments in the future and to those who are clumsy or nervously inclined.

35 40 In the drawing I have shown and in the specification described a simple embodiment of my invention.

In the drawing:

Fig. 1 is an elevation of my pack.

45 Fig. 2 is a sectional elevation showing the instruments supported within the several tubes, and

Fig. 3 is a view along the lines 3—3 of Fig. 1 showing a slightly modified form.

50 My pack consists of three tubes 1, 2, and 3 which are held in alignment by the clamp members 4 and 5 which rigidly hold the tubes 1 and 3. The tube 2 is provided with an annular recess 6 into which a protuberance 7 on the clamp member 4 fits so that while the tube 2 may be freely rotated its axial movement is extremely limited.

As shown in Fig. 3 the clamp members 4 and 5 may be detachably united as by the screws 8 to permit the tubes to be used and cleansed separately if desired.

The tube 2 has secured to its lower end as at 5 9 a resilient supporting piece 10 having flat lateral feet 10^a. When my pack is to be carried either by the clip 11 or in a leather envelope, the feet 10^a overlie the ends of the tubes 1 and 2 and are held in that position by the protuberance 7 10 bearing against the lower edge of the annular recess 6 in the tube 2.

When any of the instruments are to be used, the tube 2 and the feet 10^a are pivoted to provide for adequate support so that the pack may 15 be used as a stand. The slight axial movement of the tube 2 frees the feet 10^a so that they may lie in the same plane as the bases of the tubes 1 and 3.

20 A hypodermic syringe 12 is suspended in the liquid tight tube 3. The finger rest or shoulder 12^a of the syringe 12 overlies a rubber washer 13 positioned in the annular recess 14 in the upper end of the tube 3 which is enlarged to receive the detachable cap 15. The cap 15 has an in- 25 internal shoulder 16 which is adapted to bear against the shoulder 12^a of the syringe 12 to lock it against its rubber cushion 13. A detachable bottom 3^a is preferably provided to facilitate sterilization. 30

The tube 2 is also liquid tight and is adapted to confine the spear-head swab 17 which is attached to the cap 2^a from the tube 2. A gasket 18 prevents leakage as this tube is adapted to serve as an alcohol reservoir. The tube 1 is 35 desired to protect spare needles 19 which are held in aligned spaced position by the split sleeve 20.

The detachable caps may be secured to their respective tubes in any desired way, and the support for the tubes when my pack is to be used 40 as a stand may be variously formed, or the pack may be so formed as to permit any one of the tubes, as tube 1 for the spare needles, to be pivoted to supporting position.

45 With such an aseptic pack, a patient is able to carry a complete outfit with him. He needs only to sterilize the complete pack and contents by boiling at regular intervals. With such a pack, self treatment is made easier for the patient, not only because of the ensured sterility, 50 but also because of the accessibility of the instruments when supported as in a sterile stand.

Various modifications in the construction and assembly of my device as well as the materials used may obviously be resorted to without de- 55

parting from the spirit of my invention if within the limits of the appended claims.

What I therefore claim and desire to secure by Letters Patent is:

5. 1. A hypodermic pack unit for pocket or like transportation comprising a plurality of containers, means holding said containers in alignment and permitting one of said containers to be freely rotated and to have slight axial movement, and a support carried by said rotatable container adapted to lie in alignment with said containers and to be pivoted to support said containers in an upright position. 10
15. 2. A hypodermic pack unit for pocket or like transportation comprising a plurality of containers, members holding said containers in alignment and permitting one of said containers to be freely rotated and to have slight axial movement, a support carried by said rotatable container adapted to lie in alignment with said containers and to be pivoted to support said containers in an upright position, one of said containers having an annular recess and one of said members having a protuberance adapted to enter said recess, said protuberance and said recess being so shaped as to permit free rotation and limited axial movement of said container. 20
25. 3. A hypodermic syringe outfit comprising a triplet of containers, means holding said containers in alignment and spacing the same from each other and comprising a clamp, the outer two of said containers being rigidly held in said clamp and the middle container being rotatable therein, and a support for said containers secured to said middle container. 30
35. 4. A hypodermic syringe outfit comprising a plurality of containers, a clamp holding said containers in spaced alignment, one of said containers being rotatable in said clamp and including a support adapted on predetermined rotation of said container to hold said outfit in balanced erect position. 40
45. 5. A hypodermic syringe outfit comprising a plurality of containers, a clamp holding said containers in spaced alignment, one of said containers being rotatable in said clamp and including a support adapted on predetermined rotation of said container to hold said outfit in balanced erect position, and means limiting axial movement of said rotatable container. 50
55. 6. A hypodermic syringe outfit comprising a plurality of spaced aligned containers, one of said containers comprising a tube having an enlarged upper portion providing a shoulder, a cover for said tube having a shoulder, and a syringe comprising a flanged barrel, a washer on said barrel beneath said flange, said flange and washer being adapted to be compressibly held between the shoulder on the tube and the shoulder on the cover, and a pivoted support for said container. 60
65. 7. A hypodermic pack unit for pocket or like transportation, consisting of a plurality of tubular containers each having a closed lower flat bottom end and an upper end, detachable closures for said upper ends, means for detachably holding said containers in parallel assembly and with their lower closed flat ends in substantially the same plane, a supporting piece rotatably carried at the bottom of the middle container and having
- flat lateral feet disposable in aligned contact with the flat bottom ends of the lateral containers and rotatable to an angular position transversely of the base line of the pack end to positions of lateral support for the unit, and the mounting of said supporting piece providing for upward recession to bring the bottoms of the foot portions into the plane common to the adjacent container bottom ends. 5
8. A hypodermic pack unit for pocket or like transportation, consisting of a triplet of tubular containers of unequal length, each having a closed lower flat bottom end and an upper end, detachable closures for said upper ends, means for detachably holding said containers in parallel assembly and with their closed flat ends in substantially the same plane, a supporting piece rotatably carried at the bottom of the middle container and having flat lateral feet disposable in aligned contact with the flat bottom ends of the lateral containers and rotatable to an angular portion transversely of the base line of the pack end to positions of lateral support for the unit, and the mounting of said middle container providing for upward recession to bring the bottoms of the foot portions into the plane common to the adjacent container bottom ends. 10
9. In combination with a hypodermic syringe having a flanged barrel, a container comprising a liquid tight tube, a detachable cap for said tube, said tube and said cap including portions formed and disposed in clamping relation to said barrel flange when said cap is secured to said tube, and a compressible member between one of said members and said barrel flange. 15
10. In combination with a hypodermic syringe including a flanged barrel and a washer on said barrel below said flange, a container comprising a tube and a detachable cap for said tube, said tube and said cap including portions formed and disposed in clamping relation to said flange and said washer when said cap is attached to said tube. 20
11. A container for a hypodermic syringe having a flanged barrel, said container comprising a syringe receiving tube, and a cap adapted to be secured to said tube, said cap and said tube including resilient clamping means disposed in interlocking relation to said barrel flange when said cap is secured to said tube. 25
12. In combination with a hypodermic syringe including a flanged barrel and a gasket on said barrel below said flange, a container comprising a tube and a detachable cap for said tube, an internal support in said tube for said gasket and an internal flange in said cap adapted to bear against the upper surface of said barrel flange to provide a leakproof support for said syringe when said cap is secured to said tube. 30
13. In combination with an instrument having a gasket thereon, a container comprising a tube and a detachable cap for said tube, an internal support in said tube for said gasket and an internal flange in said cap, said flange being formed and disposed in said cap to contact and compress said gasket when said cap is secured to said tube to provide a leakproof support for said instruments. 35
